DESIGN FOR A CANDLE DRIP CATCHER

Henry W. Muller, Richmond Hill, N. Y.

Application October 29, 1937, Serial No. 72,522

Term of patent 14 years

To all whom it may concern:

Be it known that I, Henry W. Muller, a citizen of the United States, residing at Richmond Hill, in the county of Queens and State of New York, have invented a new, original, and ornamental Design for a Candle Drip Catcher, of which the following is a specification, reference being had to the accompanying drawing, forming part thereof.

In the drawing,

I claim:

The ornamental design for a candle drip catcher, as shown.

HENRY W. MULLER.
